(57) **CLAIM**

The ornamental design for an LED directional lighting device, as shown and described.

DESCRIPTION

FIG. 1 is an isometric view for an LED directional lighting device in accordance with the present design;

FIG. 2 is the front view for the LED directional lighting device shown in FIG. 1;

FIG. 3 is a back view for the LED directional lighting device shown in FIG. 1;

FIG. 4 is a right side view for the LED directional lighting device shown in FIG. 1;

FIG. 5 is a left side view for the LED directional lighting device shown in FIG. 1;

FIG. 6 is a top plan view for the LED directional lighting device shown in FIG. 1; and,

FIG. 7 is a bottom plan view for the LED directional lighting device shown in FIG. 1.
